UNITED STATES PATENT OFFICE.

HENRY SIMON, OF LAGUNA BEACH, CALIFORNIA.

RULE.

1,299,627.

Specification of Letters Patent.

Patented Apr. 8, 1919.

Application filed May 29, 1917. Serial No. 171,685.

To all whom it may concern:

Be it known that I, HENRY SIMON, a citizen of the United States, residing at Laguna Beach, in the county of Orange and State of California, have invented a new and useful Rule, of which the following is a specification.

This invention has reference to rules of the telescoping folding type, and is designed to provide a structure of exceptional strength and resistance to injury from ordinary use, and especially adapted for both interior and outside measurements, the rule being characterized by small size and extreme simplicity of construction.

A prime consideration in the construction of the rule is to obtain correct measurements without having to make allowance for errors, such measurements being accurate within an extremely small limit, say, one one-hundredth of an inch, or less.

In accordance with the invention the rule is made up of a series of telescoping members of generally tubular form and elliptical cross-section, although conformity to a true ellipse is not demanded.

The construction is such that the innermost member is provided with a head giving ample finger hold, the members are held together by friction, provision is made for integral or other stops, and the sections of the rule are made up of thin walled tubes of a conformation rendering them particularly resistant to distortion, and at the same time providing a degree of elasticity producing the desired amount of frictional engagement to hold the sections in any position of projection one with relation to the other, whereby measurements may be taken and transferred without liability of slippage of the tubes which would destroy the accuracy of the measurement.

The invention will be best understood from a consideration of the following detailed description, taken in connection with the accompanying drawings forming part of this specification, with the further understanding that while the drawings show a practical form of the invention, the latter is not confined to any strict conformity with the showing of the drawings, but may be changed and modified so long as such

changes and modifications come within the scope of the appended claims.

In the drawings:—

Figure 1 is a plan view of the sections of a four section rule removed one from the other and laid side by side.

Fig. 2 is a plan view of the assembled rule.

Fig. 3 is a longitudinal section through the assembled rule with the sections or members pulled apart for a short distance, and drawn on a larger scale than the preceding figures.

Fig. 4 is a section on line 4—4 of Fig. 2 but drawn on a larger scale.

Fig. 5 is a section similar to Fig. 4, but illustrating a modification.

Fig. 6 is a plan view of one end of one section of the rule of Fig. 5.

Fig. 7 is a plan view of a portion of another modified form of the rule.

Fig. 8 is an end view of the head end of the rule.

Figs. 9, 10, 11 and 12 are outline figures showing different shapes in which the rule may be made.

Fig. 13 is a plan view of a portion of a rule section illustrating still another modified form of the rule.

Fig. 14 is an edge view of one of the sections showing a somewhat modified construction of stop.

Referring to the drawings there is shown a rule made up of an outer section 1, an inner section 2, and intermediate sections 3, 4, respectively, the particular rule shown being a four section telescopic rule, but it will be understood that any number of sections desired may be employed. In the particular arrangement indicated in Figs. 1 and 2, the rule constitutes a two foot rule, but may be made longer or shorter by increasing or decreasing the length of the sections or increasing or decreasing the number of the sections, or both. Each section is of tubular form, preferably elliptical, or a near approach to such form and made of thin gage sheet metal.

In most of the forms shown the tubes constituting the members of the rule are made by stamping a blank out of sheet metal, and then shaping it into a flat elliptical form. When so made the sections

1, 3 and 4 are split lengthwise along one of the flatter sides, and have matching cut away portions 5, which when the blank is shaped into a tube produce a longitudinal slot 6. 5 The section 2 constituting the innermost section of the rule is not so cut away and consequently has no longitudinal slot. In section 1 the slot 6 stops short of each end of the tube, leaving an unslotted space 7 at 10 one end and an unslotted space 8 at the other end of greater length in the direction of the length of the tube than the space 7. The tubular section 3 has, at one end of the slot 6, tongues 9 folded upon themselves to 15 constitute stops for a purpose to be described. The section 3 has at the end remote from the stop 9 a portion 10 corresponding to the portion 8 of the tube 1, but of less length, and the slot 6 extends 20 closer to the corresponding end of the tube 3 than does the slot 6 of tube 1. The tubular section 4 has its slot 6 closer to the end 11 corresponding to the end 10 of the tube 3 than is the case with the tubes 1 and 3, and 25 the tube 4 has stop members 12 like the stop members 9 of tube 3.

The tube 2 constituting the innermost tube of the rule has no slot at all, but is provided with stop members 13 near one end 30 corresponding to the stop members 9 and 12 of tubes 3 and 4, but more distant from the end near which they are located than is the case with the tubes 3 and 4. The other end of the tube 2 is closed by a plug head or reinforced cap portion 14 held by rivets 15 or otherwise to the tube and this head has a cross-sectional size corresponding to the cross-section of the tube 1, so that when the tubes are nested the margins of the head 14 35 are flush with the outer walls of the tube 1, which latter is the outside and therefore the largest of the series of tubes. The tube 1 has a closure or reinforced head portion 16 for the end remote from that entered by the other tubes, and this closure may be secured 40 in place by rivets 17 or otherwise. While rivets are shown as means for fastening the head 14 and closure 16 to the respective tubes, it will be understood that any other 45 means, such as soldering and the like, may be employed, since these heads need not be disturbed after having been once secured in place in the respective tubes.

The series of telescoping tubes or members have their longitudinal axes coinciding and the cap portion 14 and head portion 16 have terminal faces of substantially equal profile axially encompassing the remaining portions of the rule.

60 Since the tubes are more or less yieldable to interior expansive forces because the tubes are longitudinally split along one edge, and, moreover, the walls of the tubes being of thin gage, that end of the tube 3 carrying

the stop 9 may be compressed or the end 8 of the tube 1 may be expanded to admit the 65 passage of the stop 9 into the tube 1 until it snaps into the slot 6, whereupon the tube 3 may be pushed into the tube 1 until the stop 9 engages the opposite end of the slot 6 at 70 the end 7 of the tube 1. The two tubes have such relative lengths that when the stop 9 engages the inner closed end of the slot 6, the other ends of the two tubes are flush one 75 with the other. Since the tubes may be made to gage and fit snugly they may further be made to slide one in the other with sufficient friction to hold them in place. To increase the frictional fit, the tubes 1, 3 and 80 4 may each have a depressed portion 18 at the ends entered by the next smaller tube in order to bear upon the next smaller tube with additional friction and such friction may be so regulated that while the tubes 85 may be drawn out or moved into each other with relative ease, they will hold the positions to which they are moved without liability of disturbance of such positions under ordinary conditions of use.

While the tube 4 is shown as of the same 90 length as the tube 3 and telescopes thereinto, the stop 12 is located at a distance from that end of the tube 4 entering the tube 3 that when it engages the stop 9 the corresponding 95 ends of the two tubes are flush. One end of the slot 6 in the tube 1 remote from the end 8 of the tube serves as an arresting means for the stop 9 and the stop 9 serves as an arresting means for the stop 12, so that when tubes 3 and 4 are within the tube 1, 100 the ends 10 and 11 of the tubes 3 and 4 are flush with the end 8 of the tube 1. The tube 2 is of a length corresponding to that of tubes 3 and 4 and the stop 13 is so located as to be arrested by the stop 12 when the 105 tube is fully telescoped into the tube 4, while the overhanging part of the head 14 engages the ends 8, 10 and 11 of the tubes 1, 3 and 4. In the particular arrangement shown the full length of the rule 1 fully telescoped is 110 seven and one-half inches, while the head 14 projects a half inch beyond the other members of the rule, thus providing ample finger space for grasping the innermost member of the rule to withdraw it, wherefore it is feasible to make the members of the rule slide as stiffly as may be desired one in the other and hence correspondingly resist disturbing forces which might change the measurements for which the rule has been set. The 115 particular measurements indicated in the drawings provide for a rule twenty-four inches long with the four sections shown in Fig. 1 when they are all drawn out to the fullest extent, while the shortest inside measurement which may be obtained is seven and one-half inches. The various sections of the rule are in alinement, and hence in- 120 125

side measurements may be very accurately taken, this not being the case with joined rules of the extension type or telescoping rules where the members are not in alignment. The various measurement lines indicated at 19 in the figures of drawing whenever they occur are carried around the sides of the members of the rule so as to facilitate marking off desired positions other than those represented by the ends only of the rule.

For the purpose of insuring accuracy the head 14 is provided on its outer face with a recess or cavity 20 in which there is lodged a scoring blade 21 held in place by a screw 22, the blade having a small lug 23 on the face toward the bottom of the cavity to seat in a groove 24 in the bottom of the cavity 20. The blade is provided with a sharp cutting end 25, as is customary in scoring blades, and the other end 26 of the blade is rounded in conformity with the corresponding end of the head 14. The blade 21 may be so situated in the cavity 20 that its cutting edge is entirely housed therein and protected from contact, or the blade may be reversed so that its cutting edge projects a short distance beyond the corresponding edge of the rule to permit the production of a knife-edge cut in the work being measured with the cut coinciding accurately with the corresponding end of the rule.

At times it is desirable to be able to produce the knife cuts at both ends of the rule, and for such purpose the closure 16 may have a scoring knife 27 lodged therein in the same manner as the scoring knife 21 with respect to the head 14. The scoring knife or blade 27 is shown in Fig. 7 and requires no further description.

In the showing of Fig. 1 and associated figures, the stops 9, 12 and 13 are produced by folded over portions of the fingers at both cut away parts 5. A somewhat more compact arrangement is provided in the structure shown in Fig. 6, where a section 3^a has a lug 9^a on one side only of the slot 6, and in this arrangement the lugs may be so positioned as to engage the end of the slot 6 in tube 1 instead of only the lug of the first tube in order entering the tube 1 so engaging. In this event all the stop lugs are at the extreme ends of the respective tubes. The two arrangements are indicated in Figs. 4 and 5. In Fig. 4 double lugs or stops 9, 12 and 13 are shown, and as they cannot pass each other, being all in the same line, they must be displaced lengthwise of the tubes. In Fig. 5 the single lugs 9^a, 12^a and 13^a, respectively, do not interfere with each other.

Instead of forming the lugs by producing tongues and folding them upon themselves laterally of the length of the slot 6, a tongue

28 may be produced at the corresponding end of the particular tube and bent upon itself lengthwise of the tube, as indicated in Fig. 14.

Again, the rule sections may be made from seamless tubing formed into shape, and one end of such a tube is indicated at 4^a in Fig. 13, it being apparent that all the tubes may be similarly formed.

The cross-sectional shape of the rule is of importance, that of Figs. 4 and 5, indicating a flat ellipse, being found to be a good form. The form of Fig. 9, which may be taken as showing a head 14^a without the scoring blade, is also a convenient form, having the faces of the rule more rounded than in Figs. 4 and 5. The showing of Fig. 10 is that of a head 14^b and indicates a rule of the same general form as that of Fig. 9, but with flats 29 on opposite faces. In Fig. 11 there is indicated a head 14^c showing what may be the cross-sectional shape of the rule, in which case one edge 30 is flat throughout nearly its whole width, while the other edge is made up of angular portions 30^a near the sides and a central flat portion 30^b parallel with the edge 30. In Fig. 12 there is indicated a head 14^d of the same general shape as would be the case in the rule shown in cross-section in Figs. 4 and 5, but with intermediate depressions 31 on opposite wide faces permitting the sinking of the stops well below the faces of the rule. The depressions or channels 31 extending lengthwise of the rule serve to stiffen the rule when extended, and reduce the liability of the rule becoming dented or injured, as well as placing the slots and stops below the general surface and entirely out of the way of harm.

Possibly the form shown in Fig. 9 is the best suited for all around work as having the advantage of an almost flat shape with facility of working with a rounded surface which imparts great strength to the rule. In fact, all the various shapes contribute to the strength of the rule, while those of Figs. 4, 10, 11 and 12 are suitable for working on flat surfaces.

In all the various shapes the edge portions are in the form of arcs of circles either actually or very closely approaching half circles. Such curved edges while just as convenient and practical for reading as the square edge of common rules, provide the greatest strength that it is possible to obtain for all the rule sections down to the innermost or smallest one, and also the greatest possible resistance to injury.

While the seamless tube of Fig. 13 is a strong construction, the split tubes have the advantage that they are elastic due to the splitting, so that the sections may be compressed laterally and longitudinally, and

thus absorb and render harmless knocks or blows or sudden twisting and side strains which might otherwise be permanently harmful. Again, the split tube permits the spreading or yielding of the ends of the rule sections entered by the smaller sections, so that such ends may spread under sudden strains without permanent enlargement which might otherwise occur.

Furthermore, the split construction has the decided advantage of providing an even and lasting friction practically unaffected by wear and not readily altered by small amounts of dust or dirt working in between the working surfaces. This is in addition to an advantage already noted in that it renders it possible to take the rule to pieces for cleaning and inspection and to reassemble it easily and quickly without the necessity of the use of any tools or the removal of any fastening means.

What is claimed is:—

1. An extension rule comprising a series of telescoping members with their longitudinal axes coinciding, the innermost and outermost members being provided at their respectively outer ends with terminal portions having outer faces of substantially equal profile and pierced by the common longitudinal axis of the members at the same relative points, and all portions of the rule between the outer faces of the terminal portions being substantially contained within a body made by the projection of the profile of the outer faces of the terminal portions parallel with the longitudinal axis of the rule, whereby the rule can be laid down flat on any plane surface in any position or stage of extension with corresponding points of the outer faces of both terminal portions touching the flat surface and the common axis of the tubes parallel to the flat surface, to render possible the use of the rule for measuring distances on any flat surface along any side or edge of the rule.

2. An extension rule comprising a series of telescoping members with their longitudinal axes coinciding, the outermost member being provided at its outer end with a cap portion and the innermost member at the corresponding opposite end with a thickened head portion having an extent lengthwise of the body of the rule to provide a hold for the fingers of the human hand for extending the rule, the cap portion and head portion having terminal faces of substantially equal profile axially encompassing all remaining portions of the rule, the projected end elevations of the rule thus being substantially equal and coaxial and all portions of the rule being contained within the compass of the projected end elevations of the rule.

3. An extension rule comprising a series of telescoping members with their longitudinal axes coinciding and with the innermost member having at one end a lateral area corresponding to the cross sectional area of the outermost member and, when the rule is closed, constituting a cover for those ends of the other members presented toward the head.

4. An extension rule comprising a series of telescoping tubes with their longitudinal axes coinciding and with the innermost tube provided with a terminal head having a lateral area corresponding to the cross sectional area of the outermost tube, and the corresponding ends of all the tubes outside of the innermost tube substantially abutting the head when the rule is closed.

5. An extension rule comprising a series of telescoping members with their longitudinal axes coinciding and the innermost member provided with a terminal head constituting a cover for those ends of the other members presented toward the head, and said head being of an axial length to be grasped by the fingers of the human hand for extending and contracting the rule.

6. An extension rule comprising a series of telescoping members with the innermost member having a head at its outer end of a lateral extent corresponding to the cross-sectional area of the outermost one of the members, and a marking blade carried by the head flush with that face of the head remote from the body of the rule.

7. An extension rule comprising a series of telescoping members with the innermost member having a head at one end of a lateral extent corresponding to the cross-sectional area of the outermost member, and a marking blade carried by the head flush with the face of the head remote from the body of the rule and normally flush with the margin of the head, said marking blade being eccentrically mounted for the projection of the blade beyond the marginal portion of the head.

8. An extension rule comprising a series of telescoping members with the innermost member having a head at its outer end of a lateral extent corresponding to the cross-sectional area of the outermost one of the members, and a marking blade carried by the head flush with that face of the head remote from the body of the rule, and the rule also being provided with a marking blade at the end remote from said head.

9. An extension rule comprising a series of telescoping members with the innermost member having a head at one end of a lateral extent corresponding to the cross-sectional area of the outermost member, and a marking blade carried by the head flush with

- the face of the head remote from the body of the rule and normally flush with the margin of the head, said marking blade being eccentrically mounted for the projection of the blade beyond the marginal portion of the head, and said rule also being provided with a marking blade at the end of the rule remote from said head and mounted for the projection of the marking portion of the blade into operative position from a normally flush relation to the marginal portion of the rule.
10. An extension rule comprising a series of alined telescoping members with the ends 15 of the rule of substantially the same cross sectional area, said rule being provided with permanently placed terminal marking means normally located wholly within the cross sectional area of the rule and movable there- 20 beyond for marking purposes in a direction perpendicular to the longitudinal axis of the rule.
11. An extension rule comprising a series of alined telescoping members and pro- 25 vided with terminal marking means nor- mally flush with the ends of the rule, said marking means being capable of projection into operative position by a movement sub- stantially perpendicular to the longitudinal 30 axis of the rule.
12. An extension rule, comprising a series of telescoping members each provided with means for arresting it when pulled out to a predetermined limit and the arresting means 35 on the successive members being progres- sively spaced closer to the ends of said mem- bers.
13. An extension rule comprising a series of telescoping members with each member 40 smaller than the outermost member provided with a projecting stop and each member larger than the innermost member having a longitudinal slot receiving the stop of the next smaller member, the stops being ar- 45 ranged at different distances from the cor- responding ends of the members on which they are located, whereby all the inner mem- bers larger than the innermost member may be wholly lodged within the outer member.
- 50 14. An extension rule comprising a series of telescoping tubes with each tube smaller than the outermost tube provided with a projecting stop near one end and each tube larger than the innermost tube having a 55 longitudinal slot receiving the stop of the next smaller tube, the stops being arranged at different distances from the correspond- ing ends of the tubes on which they are lo- cated, whereby all the inner tubes larger 60 than the innermost tube may be wholly lodged within the outermost tube, and the slots of the inner slotted tubes approaching progressively closer to the opposite ends of
- said tubes remote from the stops than the slot of the outermost tube.
15. An extension rule comprising a series of telescoping tubes with each larger tube having a longitudinal slot and each smaller tube having a stop member engaging in the slot of the next larger tube, and the inner- 70 most tube being provided with a head of a size corresponding to the cross-sectional area of the outermost tube, whereby the head provides a hand hold for extending the rule, and the rule when closed is of substantially 75 the same cross-sectional area throughout its length.
16. An extension rule comprising a tele- 80 scoping series of thin metal tubes of ellipti- cal conformation, each tube being split lengthwise to elastically grip the next smaller tube, and the innermost and outer- most tubes having closures at respectively opposite ends with the end closure of the innermost tube of a lateral spread to an ex- 85 tent corresponding to the cross-sectional size of the outermost tube and forming an abut- ment for all the tubes larger than the inner- most tube.
17. An extension rule comprising a series 90 of telescoping metallic tubes of greater width than thickness and of thin gage, and also having the long edges of the rule rounded, the innermost tube of the series be- 95 ing provided with a terminal head having a lateral area equal to the cross sectional area of the outermost tube.
18. An extension rule comprising a tele- 100 scoping series of thin gage tubes of ellipti- cal cross section and split throughout their entire length, the innermost tube of the series having a head of a lateral extent equal to the cross sectional area of the innermost tube and forming an abutment for the cor- 105 responding ends of all the tubes exterior to the innermost tube.
19. An extension rule comprising a tele- 110 scoping series of thin gage tubes of ellipti- cal cross section and split throughout their entire length, the innermost tube of the series having a head of a lateral extent equal to the cross sectional area of the innermost tube and forming an abutment for the corre- 115 sponding ends of all the tubes exterior to the innermost tube, and the head being provided with a marking blade normally flush there- with.
20. An extension rule comprising a tele- 120 scoping series of thin gage tubes of ellipti- cal cross section and split throughout their entire length, the innermost tube of the series having a head of a lateral extent equal to the cross sectional area of the innermost tube and forming an abutment for the corre- 125 sponding ends of all the tubes exterior to the innermost tube, and the head being provided

with a marking blade normally flush therewith, said blade being mounted eccentrically in the head and movable about its axis to project beyond the margin of the head for marking purposes.

21. An extension rule comprising a telescoping series of thin tubes of elliptical conformation, the innermost and outermost tubes having closures at respectively opposite ends, with the end closure of the innermost tube of a lateral spread, corresponding to the cross-sectional size of the outermost tube and forming an abutment for all the tubes larger than the innermost tube.

Copies of this patent may be obtained for five cents each, by addressing the "Commissioner of Patents, Washington, D. C."

22. An extension rule comprising a telescoping series of thin tubes of elliptical conformation and channelled longitudinally.

23. An extension rule comprising a series of thin-walled telescoping tubes of greater width than thickness and channelled longitudinally between the sides.

In testimony, that I claim the foregoing as my own, I have hereto affixed my signature in the presence of two witnesses.

HENRY SIMON.
